UNITED STATES PATENT OFFICE.

ALBERT A. LOVE, OF NEW BRIGHTON, NEW YORK.

PLATE AND DISH.

SPECIFICATION forming part of Letters Patent No. 226,665, dated April 27, 1880.

Application filed March 10, 1880. (No model.)

To all whom it may concern:

Be it known that I, ALBERT A. LOVE, a subject of the Queen of Great Britain, residing in the town of New Brighton, county of 5 Richmond, and State of New York, have invented certain new and useful Improvements in Plates, Dishes, &c., fully described and represented in the following specification and the accompanying drawings, forming a part 10 of the same.

In said drawings, Figure 1 illustrates a plate or shallow dish, the edge or rim of which is enlarged on its under side. Fig. 2 illustrates such a plate or dish with its edge or 15 rim enlarged on its upper side, and Fig. 3 illustrates such a plate or dish with its rim or edge enlarged on both its upper and under side.

The fragile character of the material of 20 which ceramic plates, dishes, &c., constituting table-ware are composed renders them liable to disfigurement by the chipping or abrading of their projecting edges or rims, which results from the forcible contact of one 25 dish with another, either in packing, handling, or use. Such injury destroys their salability if it occurs in the hands of the trade, and renders them unsightly, undesirable, and often useless if it occurs in the hands of the 30 user.

Attempts have been made to remedy these 35 defects by constructing the said plates, dishes, &c., with very thick bodies, so as to provide them with thick and strong rims or edges; but this method adds to the article very objectionable elements—namely, such thickness and weight as to render them cumbersome, 40 unhandy, and expensive—and when adopted in fine porcelain goods detracts from their salability, (while increasing their cost,) for the reason that a most desirable quality of such goods is lost—namely, such a thinness of body as to produce transluce-

The present invention, which consists in 45 forming an enlargement or bead upon the edges or rims of ceramic wares, such as dishes, plates, &c., is alike applicable to fine porcelain goods and to the coarser grades of earthenwares, imparting to the former, without in- 50 creasing the thickness of the body portion,

rims or edges having a proper degree of strength to resist ordinary blows, and, while in like manner protecting the rims or edges of the coarser goods, enabling their body portions to be made considerably lighter than is now 5: the practice.

In carrying out this invention the plate or dish, of whatever general conformation or shape, is formed by the potter in the usual manner, and during such forming the edge or 6: rim is enlarged on its under side or upper side, or both, so as to provide the same with the enlargement or bead *a*, as shown in the drawings. When the ware is fired this enlargement or bead is rendered not only as hard and 6: tenacious as the other portions of the article, but, from its increased body of material, its strength is materially increased beyond that possessed by the thinner portions thereof.

Plates, dishes, and like flat ware, whether 7: of fine or coarse grade, when thus constructed may be handled and brought into contact with each other, or with hard surfaces, without danger of their edges becoming chipped or otherwise damaged.

Articles so improved may be made with 7: comparatively thin bodies, and yet possess the qualities of superior strength and durability, enhanced beauty of finish, and cheapness of production, for the reasons that the 8: enlarged rim or edge not only stiffens the thin body of the article, but resists the destructive blows against its edge, while it imparts an ornamental finish, and enables the article to be formed from a lesser quantity of material 8: than is now employed.

This improvement thus adapts the coarser 9: grades of goods for the supply of a trade now compelled to use a fine and costly article, and adapts the finer grades of goods for use where 9: the coarser are necessarily employed because great strength is required.

The improvement may, of course, be applied to all vitreous wares, the enlargement or rim *a* being produced, as the article is formed, 9: by blowing or casting.

Having now described the improvement and the merits it possesses, what is claimed is—

A plate or similar article of table-ware con- 10

structed of a base from which a flange or wall rises on all sides to form a hollow vessel, said flange or wall having smooth uninterrupted exterior and interior surfaces, and enlarged at its outer edge to provide it with a protecting-rim, *a*, all substantially as described.

In testimony whereof I have hereunto set

my hand in the presence of two subscribing witnesses.

ALBERT A. LOVE.

Witnesses:

H. T. MUNSON,
GEO. H. GRAHAM.
